UNITED STATES PATENT OFFICE.

JAMES A. CAREY, OF PITTSBURGH, PENNSYLVANIA.

SUPPORT FOR CONTAINERS.

1,400,025.

Specification of Letters Patent. Patented Dec. 13, 1921.

Application filed September 4, 1920. Serial No. 408,115.

To all whom it may concern:

Be it known that I, JAMES A. CAREY, a citizen of the United States, and resident of Pittsburgh, in the county of Allegheny and State of Pennsylvania, have invented a new and useful Improvement in Supports for Containers; and I do hereby declare the following to be a full, clear, and exact description thereof.

10 My invention relates to a holder or support for carboys or similar receptacles which is designed to support the carboy in such manner that the carboy may be readily tilted for the purpose of emptying its contents.

15 According to present practice carboys are usually packed in wooden crates or boxes, through the top of which the neck of the bottle projects. It is an object of the present invention to provide a holder preferably adapted to engage this crate and support the carboy, the holder having trunnions for engagement with a suitable support whereby the carboy may be tilted. With a modification, however, the invention may be applied to bottles or carboys not protected by crates.

20 It is a further object of the invention to provide a holder adjustable for carboys of different sizes, inasmuch as they often vary within a few inches of each other.

25 My invention is illustrated in the accompanying drawings, in which Figure 1 is a perspective view showing the preferred form of my invention. Fig. 2 is a vertical longitudinal section through the center of Fig. 1. Fig. 3 shows a perspective view of a modification of my invention. Fig. 4 shows a perspective view of another modification of the invention.

30 In the drawings, 5 represents a carboy packed in a crate or box 6, the crate having the usual side strips 7, these strips being provided on practically all carboy boxes.

35 My invention comprises end members 8 adapted to engage the under side of the strips 7, these end members being formed of metallic bars having vertically depending portions 9 between their ends, which depending portions are integral therewith, as shown, or otherwise rigidly connected thereto. Secured to the members 8 and also midway between the ends thereof are bosses 10 from which project trunnions 11 having end portions 12 of larger diameter, the reduced portion 11 forming the bearing surface of the trunnion. The end portions 12 form han-

dles by means of which a carboy may be conveniently transported from one place to another. Passing through the ends of the bars 8 are removable connecting bolts 13 provided with wing nuts 14.

40 The lower ends of the depending portions 9 are preferably provided with a vertical series of holes 15. A flat strip 16 having threaded projections 17 forms a connection for the depending portions 9. Nuts 18 on the extensions 17 provide means for adjusting the spacing between the depending portions 9. By passing the extensions 17 through different holes 15 in the vertical series 45 vertical adjustment of the strip 16 may be effected.

45 From the foregoing it will be seen that the bars 8 and the flat strip 16 form means for clamping and supporting the carboy and that the bolts 13 serve as means for drawing the bars 8 together into clamping engagement with the sides of the container and also serve as side supports for retaining the carboy in position. The depending side frame members 9 also frictionally engage the carboy or the crate in which it is contained to aid in clamping the receptacle and supporting it. Furthermore, the end members maintain the container rigid and prevent lateral 50 play when the container is turned to inverted position.

55 Any suitable means may be provided for pivotally supporting the carboy on the trunnions, but I prefer to use a frame of the kind shown in Fig. 1, which comprises a pair of triangular shaped end sections 19 connected together by rods 20 which are preferably threaded and provided with nuts 21. These rods or bolts 20 permit the length 55 of the frame to be adjusted. Concave bearing surfaces for the reduced portion 11 of the trunnions are provided at 22. By reason of the shoulders on the trunnions formed by the reduced portion 11, the tops of the frames are held in proper spaced relation and rigidity is given to the frame.

60 In the modification shown in Fig. 3, the bottom strip 16, instead of being a separate strip, is formed integral with the depending portions 9 and no adjustment thereof is provided. The trunnions are shown as being supported on a receptacle 23 of suitable acid resisting material.

65 In the modification shown in Fig. 4 the construction is similar to that shown in the other figures, but differs in that the hori-

zontal bars 8 of the end members are curved to conform substantially to the curvature of a bottle 25 of given size, and the bolts 13 are considerably shorter than in the other 5 forms of the invention.

A felt or other liner 26 may be provided for the inner surface of the curved bars 8.

In all of the various constructions illustrated and described herein, it will be seen that the center of gravity of the container is below the pivot point and in vertical alinement with the pivots, so that the container normally assumes a substantially vertical position. To empty the contents of the container it may be readily tilted on the trunnions without danger of splashing or unexpected spilling. The support clamps the container or its crate sufficiently tight to prevent the container from moving or falling out when it is tilted.

I claim as my invention:

1. A support for containers comprising horizontal end members, trunnions on said members, depending vertical portions on 25 said end members rigidly connected therewith and in alinement with the trunnions, said end members having a series of openings therein, a cross member having means thereon for engaging in the openings for 30 adjustably connecting the lower ends of the depending portions, and a supporting member having bearings therein for coöperating with the trunnions.

2. A support for containers comprising 35 horizontal end members, trunnions on said end members, depending vertical portions on said end members and in alinement with the trunnions, a cross member connecting the lower ends of the depending portions and 40 forming a support for the bottom of the container, said cross member being adjustable vertically and longitudinally with relation to the depending portions, and a supporting means having bearings thereon for 45 coöperating with the trunnions.

3. A support for containers comprising horizontal end members, trunnions on said 50 end members, depending vertical portions on said end members formed integrally with the horizontal end members, bolts at each side of the container connecting the end members, said bolts permitting of the adjustment of said end members toward and from each other, a frame comprising end 55 sections, bearings on said end sections for the trunnions, adjustable means for connecting the bottoms of the end sections whereby

the frame may be adjusted to receive containers of varying sizes, and means on the trunnions comprising shoulders for holding 60 the tops of the end sections in proper spaced relation.

4. The combination with a container carried in a protecting crate, said crate having side strips thereon, of means for pivotally supporting the container and crate comprising end members adapted to engage the sides of the crate and the under side of the strips, trunnions on said end members, depending vertical portions on said end members and in alinement with the trunnions and adapted to engage the sides of the crate, clamping rods connecting the end members at each side of the crate, a cross member connecting the ends of the depending portions and providing a support for the container, and means providing a bearing for the trunnions.

5. The combination with a container carried in a protecting crate, said crate having 80 side strips thereon, of means for supporting the container and crate comprising end members having depending portions rigidly connected thereto, said end members and depending portions being adapted to frictionally engage the sides of the crate and the side strips thereon, trunnions on said end members, clamping rods at each side of the crate for connecting the end members and holding them in clamped relation therewith, and a supporting stand having means thereon coöperating with the trunnions.

6. A support for containers comprising a pair of end members adapted to be clamped to two sides of a container, rods for connecting the end members and holding them in clamped relation, and trunnions carried by said end members, each of said trunnions having means thereon for providing a bearing portion and being extended to form handle portions beyond the bearing portions by means of which a container may be pivotally supported or conveniently carried after the end members have been clamped thereto, the bearing portion being formed between 105 shoulders on the trunnion, and a supporting stand having means thereon coöperating with the bearing portions of the trunnions.

In testimony whereof, I, the said JAMES A. CAREY, have hereunto set my hand.

JAMES A. CAREY.

Witness:

J. M. GEOGHEGAN.
